UNITED STATES PATENT OFFICE

127,948

DESIGN FOR A CASING FOR SOUND APPARATUS

David C. Rockola, Chicago, Ill., assignor to Rock-Ola Manufacturing Corporation, Chicago, Ill., a corporation of Delaware

Application February 5, 1941, Serial No. 98,745

Term of patent 3½ years

To all whom it may concern:

Be it known that I, David C. Rockola, a citizen of the United States, residing at Chicago, in the county of Cook and State of Illinois, have invented a new, original, and ornamental Design for a Casing for Sound Apparatus, of which the following is a specification, reference being had to the accompanying drawing, forming a part thereof.

The drawing is a perspective view of a casing for sound apparatus showing my new design.

The design of the side portion of the casing not shown in the drawing corresponds to the design of the portion that is shown in the drawing. The top of the casing is open.

I claim:

The ornamental design for a casing for sound apparatus, as shown and described.

DAVID C. ROCKOLA.
